ABSTRACT OF THE DISCLOSURE

Frequency modulator having alternately conductive stages of a transistor multivibrator connected in series with respective constant-current devices, preferably also transistors, whose conductivity is controlled by an applied biasing voltage, the emitters of the two multivibrator stages being interconnected through a condenser whose charging voltage triggers the switchover of the multivibrator upon attainment of a predetermined level of either polarity.

My present invention relates to a linearly controllable frequency modulator of the multivibrator type.

The general object of my invention is to provide a frequency modulator using a transistor multivibrator which may be linearly controlled by an input voltage over a wide range of frequencies and whose output has a virtually invariable waveshape and, preferably, a constant amplitude over its entire frequency range.

Generally, astable transistor multivibrators have a period which depends on the exponential charge and/or discharge of a storage element, such as a condenser. A reasonably linear frequency control of such multivibrators may be achieved only over a narrow range if the storage element is charged through a variable passive impedance or through an ordinary variable-gain amplifier. In the modulator according to my invention a capacitor (or group of capacitors) connected across the input electrodes of two multivibrator stages is linearly charged with alternating polarity by way of a pair of voltage-controlled constant-current devices, advantageously transistors, having the same modulating voltage applied thereto; with the switchover rate of the multivibrator high compared to the maximum frequency of the modulating input signal, there results a square-wave output voltage whose waveshape is independent of the instantaneous signal level. Thus, the positive and negative portions of the multivibrator output cycle have a fixed time ratio (possibly 1:1) determined by the impedance ratio of the two current paths through the aforementioned constant-current devices. With application of a clamping voltage to a control electrode of one of the multivibrator stages in the conductive condition thereof, one output terminal of the multivibrator has an output whose amplitude swing remains constant for all modulating voltages.

The invention will be described in greater detail with reference to the accompanying drawing in which:

FIG. 1 is a circuit diagram of a modulator according to my invention; and

FIG. 2 is a diagrammatic representation of the waveforms associated with the modulator of FIG. 1.

In FIG. 1 a pair of transistors T₃ and T₄, shown to be of the NPN type, represent two voltage-controlled constant-current devices. The bases of transistors T₃ and T₄ are grounded. Two series-connected resistors R₃ and R₄ connect the emitters of transistors T₃ and T₄ to a point of fixed biasing voltage V₀ in series with a common further resistor R₅. A modulating input voltage V_{in}, developed

2

across a grounded resistor R₆, is applied via an input terminal I_T to the junction of resistors R₃, R₄ and R₅ through a coupling condenser C_s of large capacitance. The collectors of transistors T₃ and T₄, carrying currents I₁ and I₂ of a magnitude dependent on the input signal V_{in}, are connected to respective emitters of another pair of transistors T₁ and T₂, also of the NPN type, which form respective stages of an astable multivibrator. A switching capacitor C is connected across the emitters of transistors T₁ and T₂. The base of transistor T₁ is connected to a source of fixed biasing voltage V_b; the base of transistor T₂ and the collector of transistor T₁ are tied together and connected to a source of positive driving voltage V₁ through a resistor R₁ and to a source of somewhat lower clamping voltage V_d through a diode D so poled as to be reverse-biased by the potential difference V₁—V_d when the transistor T₁ is cut off. A source of positive driving voltage V₂, higher than V₁, is connected to the collector of transistor T₂ by way of a resistor R₂. Output terminals 1 and 2 are tied to the collectors of multivibrator stages T₁ and T₂, respectively.

In FIG. 2 the variations of the emitter and collector voltages V_{e1}, V_{e2} and V_{c1}, V_{c2} of transistors T₁, T₂ have been plotted, together with the fixed voltages V₁, V₂, V_b and V_d, during one cycle of the multivibrator. The cycle has a length t equal to the sum of the intervals t' and t'' during which the transistors T₁ and T₂ are respectively conductive.

During the operation of the multivibrator T₁, T₂ the capacitor C is charged in one sense or the other, depending on which of its stages is conductive. At instant t₀, the polarity of the charge is such that voltage V_{e2} is positive with respect to voltage V_{e1}. With transistor T₁ turned on and transistor T₂ cut off, the emitter current of transistor T₁ splits into a branch I₁ passing through transistor T₃ and a branch I₂ which flows through transistor T₄ in series with capacitor C, thereby charging this capacitor in the reverse sense at a uniform rate. Throughout the interval t' the voltage V_{e2} drops at a constant rate determined by the current I₂ until, at a time t₁, it becomes slightly less than the voltage V_{c1} and trips transistor T₂ into conduction. This operation drives the emitter of transistor T₂ more positive and, through condenser C, applies a positive switching pulse to the emitter of transistor T₁ which is thereby cut off while its collector potential V_{c1} jumps from the clamping voltage V_d to the driving voltage V₁. During the ensuing interval t'', the emitter current of transistor T₂ splits into a branch I₂, passing through the transistor T₄, and a branch I₁ which traverses the transistor T₃ in series with a capacitor C, thereby linearly charging this capacitor in the original sense to restore, at time t₂, the condition existing at time t₀, i.e. at the beginning of the cycle.

The operating period t=1/f (f being the output frequency) is directly related to the time necessary to charge the capacitor C to a level corresponding to either the clamping voltage V_d (interval t') or the biasing voltage V_b (interval t''), the jump in emitter voltage having the same invariable magnitude $\Delta V=V_1-V_d$ during each switchover. The magnitude of the charging currents I₁, I₂, and therefore the duration of charging intervals t'' and t', is a function of the applied signal voltage V_{in}. The output voltage V_{out} at terminal 1 varies between the supply voltage V₁ and the clamping voltage V_d, independently of frequency, and is therefore always equal to ΔV . At terminal 2 the voltage V_{out} rises to a maximum of V₂ when transistor T₂ is cut off, but its minimum value depends on the voltage drop across resistor R₂ during conduction of that stage which in turn is determined by the magnitude of the currents I₁ and I₂. During negative half-cycles of the input signal V_{in} the currents I₁ and I₂ are relatively high, causing a greater voltage drop across

resistor R_2 upon conduction of transistor T_2 along with a higher operating frequency f ; during positive half-cycles the charging currents are relatively low, the frequency drops and the voltage swing on terminal V''_{out} is reduced.

The clamping circuit including voltage source V_d and diode D can be omitted if the parameters of the system are so chosen that transistor T_1 invariably saturates during cutoff of transistor T_2 , irrespectively of the amplitude of the applied modulating voltage V_{in} . In that case the terminal voltage V'_{out} will vary between V_1 and $(V_1 - R_1 I_{sat})$, I_{sat} being the saturation current of stage T_1 ; the operating frequency f will then be determined exclusively by the magnitude of I_1 during charging period t'' in which the nonsaturating transistor T_2 conducts.

I claim:

1. A frequency modulator comprising an astable multivibrator with two stages interconnected for alternate conduction and provided with respective input electrodes; a first and a second constant-current device respectively connected in series with said stages and provided each with a respective control electrode; condenser means connected between said input electrodes for triggering a switchover between said stages upon attainment by said condenser means of a charging voltage of predetermined magnitude of either polarity; and a common control circuit for said stages including an input terminal connected in parallel to the control electrodes of said constant-current devices for varying their conductivity in response to an input signal applied to said terminal, thereby altering the length of an operating cycle of said multivibrator.

2. A frequency modulator as defined in claim 1 wherein said stages are a first and a second transistor, said input electrodes being emitters of said transistors.

3. A frequency modulator as defined in claim 2 wherein said constant-current devices are a third and a fourth transistor.

4. A frequency modulator as defined in claim 3 wherein said third and fourth transistors have emitters connected in parallel, as said control electrodes, in said common circuit.

5. A frequency modulator as defined in claim 4 wherein said first transistor has a collector connected to a source of a first fixed driving voltage through a first resistor, said second transistor having a collector connected to a source of a second fixed driving voltage through a second resistor, said first transistor having a base connected to a source of fixed biasing potential, said second transistor having a base connected to the collector of said first transistor.

10 6. A frequency modulator as defined in claim 5, further comprising diode means for connecting the collector of said first transistor to a source of fixed clamping potential in the conductive condition of said first transistor.

7. A frequency modulator as defined in claim 5, further comprising an output lead connected to the collector of said first transistor.

8. A frequency modulator as defined in claim 4, further comprising a third and a fourth resistor connected between the emitters of said third and fourth transistors, respectively, and said common circuit.

20 9. A frequency modulator as defined in claim 8 wherein said common circuit includes a further resistor in series with a source of constant voltage, said terminal being capacitively connected to a common junction of said third, 25 fourth and further resistors.
